UNITED STATES PATENT OFFICE.

DOUGLAS RIDER, OF LONDON, ENGLAND, ASSIGNOR TO THERMAL INDUSTRIAL AND CHEMICAL (T. I. C.) RESEARCH COMPANY LIMITED, OF LONDON, ENGLAND, A BRITISH COMPANY.

DEHYDRATION AND DISTILLATION OF TARS OR OILS.

Application filed February 28, 1924, Serial No. 695,765, and in Great Britain April 10, 1923.

This invention relates to improvements in the process of dehydrating and distilling tars or oils by passing the liquid to be treated through pipes or containers immersed in a 5 bath of molten metal or alloy. According to the invention the temperature of the molten metal or alloy is controlled so that it exceeds by a few degrees only the boiling point of the highest boiling distillate which 10 it is desired to obtain. For instance, in the case of the dehydration of tar or the distillation from it of lighter fractions, this excess of temperature would be in the neighbourhood of 10-15° C., but when heavier fractions 15 are being distilled the difference of temperature would be greater. Since the liquid coming into contact with the inner walls of the pipes or containers is never subjected to an excessive temperature, over-heating or 20 cracking of the liquid or distillates and the consequent deposition of carbon on the walls is minimized or eliminated and the pipes or containers always remain substantially clean, so that the transmission of heat is maintained. 25 The life of the pipes or containers is prolonged.

In the event of the core of the liquid within the pipe or container not being heated to the same extent as the layer nearest the heat- 30 ed walls, or in the event of the core of the liquid not being distilled to the same extent as the outer layer, the liquid and vapours may be released from the pipe or container into the bath of molten metal in such 35 a way that the liquid is allowed to spread over the surface of the molten metal in an even, thin layer so that the whole of the liquid is brought to a uniform temperature and distilled to the same extent.

40 As the molten metal or alloy is constant in temperature the more highly heated liquid emerging from the pipe cannot be further heated or distilled whilst the less highly heated liquid can be brought to the desired temperature and the necessary distillates removed. The combination of the two methods of heating and distilling referred to above allows use of a smaller apparatus than could be used if either method were used alone, and a better thermal efficiency is obtained.

A suitable apparatus comprises a still containing molten metal or alloy in which is immersed a pipe of suitable length having its

discharge end above the surface of the metal. 55 The liquid is caused to flow through the pipe at a suitable rate and to issue from its discharge end so as to flow over the surface of the molten metal. The vapours are collected from the still in the usual manner and the 60 residue issues from an overflow pipe so that the process may be continuous.

The accompanying drawings illustrate a suitable apparatus, Fig. 1 being a vertical section and Fig. 2 a horizontal section on line 65 2-2 of Fig. 1.

The still *a* contains a spiral pipe *b* of which the admission end *c* extends through the wall of the still while the delivery end *d* is upwardly turned so that it protrudes above the 70 surface *e* of the molten metal or alloy, the greater part of the pipe being submerged beneath the surface. The pipe is supported by two struts *f* from the wall of the still.

The tar or oil is heated as it flows through 75 the spiral pipe and such portion as is not vaporized therein flows from the open end *d* on to the surface of the metal or alloy. Here it travels in the form of a thin layer 80 towards the outlet *g*, its path being protracted by a spiral plate *h* supported on the pipe so that a part of it is immersed in the molten metal. Matter which will not volatilize at the temperature of the metal leaves the still by the outlet *g*. 85

The tube *i* contains any known thermostatic device for keeping the temperature at the desired degree, or a pyrometric device.

Having thus described the nature of the said invention and the best means I know of 90 carrying the same into practical effect, I claim:—

A process of dehydrating and fractionally distilling tars or oils, which consists in passing the liquid to be treated through a duct 95 immersed in a bath of molten metal, maintaining the temperature of the molten metal at a point which exceeds by a few degrees only the boiling point of the fraction which it is desired to vaporize, and causing the liquid 100 to issue from the said duct above the surface of the molten metal in such a manner that the liquid spreads over the surface of the molten metal in an even layer.

In testimony whereof I have signed my 105 name to this specification.

DOUGLAS RIDER.
